UNITED STATES PATENT OFFICE.

JOSEPH VERCHAK, OF NUTTER FORT, WEST VIRGINIA.

SHIP-RAISING DEVICE.

1,384,931.

Specification of Letters Patent. Patented July 19, 1921.

Application filed February 2, 1921. Serial No. 441,962.

To all whom it may concern:

Be it known that I, JOSEPH VERCHAK, a citizen of Jugo-Slavia, residing at Nutter Fort, in the county of Harrison and State of West Virginia, have invented certain new and useful Improvements in Ship-Raising Devices, of which the following is a specification.

This invention relates to certain new and useful improvements in ship raising devices and has particular reference to a device for raising sunken vessels to the surface of the water when the hull thereof has become damaged.

15 The primary object of the invention is to provide a ship with a plurality of inflatable gas bags normally deflated and positioned within the casing and inflatable at will to cause a damaged ship to float upon the surface of the water and prevent sinking thereof.

A further object of the invention is to provide a ship raising device wherein the main deck of a ship carries a plurality of 25 box - like casings containing normally deflated gas bags with gas producing agents arranged in the casings and adapted to be operated for inflating the bags to maintain the ship upon the surface of the water when 30 the hull of the ship becomes damaged.

With the above and other objects in view, the present invention consists in the novel form, combination and arrangement of parts hereinafter more fully described in connection with the accompanying drawings and 35 in which like reference characters designate corresponding parts throughout the several views.

In the drawings,

40 Figure 1 is a side elevational view of a ship equipped with the present invention, the gas bags being shown by dotted lines and broken away,

45 Fig. 2 is a top plan view of the ship showing the box-like casings inclosing the gas bags,

Fig. 3 is a rear elevational view showing the bags inflated and projecting upwardly 50 from the ship,

55 Fig. 4 is a detail sectional view of one of the box casings for inclosing a deflated gas bag,

Fig. 5 is a fragmentary top plan view of one of the box casings with the hinged 55 cover removed showing the receptacle with-

in the casing that contains the gas producing agent,

Fig. 6 is a detail sectional view of the receptacle containing the gas producing agent and the electric spark device for igniting the wick for producing the buoyant gas,

Fig. 7 is a cross sectional view taken on line VII—VII of Fig. 6 showing the gas producing wick within the receptacle, and

Fig. 8 is a detail sectional view showing the electric spark device for igniting the gas producing wick.

Briefly described, the present invention aims to provide a ship raising device where- 70 in the deck of a ship is provided with a plurality of box-like casings having hinged covers arranged adjacent the gunwale of the ship. A funnel - shaped receptacle is in- closed within each casing and contains a gas 75 producing wick adapted to be ignited by an electric spark device. A normally deflated gas bag has the mouth portion thereof se- 80 cured to the upper end of the funnel-shaped receptacle and upon ignition of the wick, the bags will be inflated and automatically open the covers of the box casings to be extended therefrom for maintaining the ship floatative upon the surface of the water. An individ- 85 ual sparking device may be associated with each receptacle or the receptacles may be connected in series to cause a simultaneous inflation of each bag upon the operation of a single switch.

Referring more in detail to the accom- 90 panying drawings, there is illustrated a ship 1 having the usual deck portion 2 with a series of box casings 3 anchored to the deck as at 4 in proximity of the gunwale 5 of the ship. The box casings 3 include covers 95 6 hinged thereto as at 7 with the weight of the covers normally maintaining the same in the closed positions shown in Figs. 2 and 4.

A gas producing device and gas bag are positioned in each box casing 3 and includes 100 a receptacle 8 of funnel-shape, as best illus- trated in Figs. 4 to 8, the receptacle includ- ing a base flange 9 anchored as at 10 to the bottom wall of the box casing 3 and the deck 2. A threaded mouth 11 projects from 105 the upper end of the receptacle 8 and re- ceives the threaded flange 12 of the funnel 13. A gas bag 14 having a reduced neck 15, has the neck portion thereof received on the funnel 13 and securely clamped in position 110

by the strap 16. To brace the bag 14 when in inflated condition, links 17 are connected at their upper ends to lugs 18 carried by the bag mouth 15 and at their lower ends to the lugs 19 carried by the receptacle 8, this construction being more clearly shown in Fig. 6.

The gas producing mechanism includes a short tube 20 extending through the deck 2 and bottom wall of the box casing 3 and upwardly into the receptacle 8, the same being preferably formed integral with the bottom wall of the receptacle as shown in Fig. 6. A gas producing wick 21 is positioned in the receptacle 8 and has one end thereof secured in the open upper end of the tube 20. To ignite the wick 21 a pair of electric sparking contacts 22 are connected to and insulated from the tube 20 with the sparking end thereof arranged adjacent the end of the wick 21 within the upper end of the tube as shown in Fig. 8 while line wires 23 extending from the contacts 22 lead to the battery 24 and are controlled by the switch 25. As a brace to the hull of the ship, and to more securely anchor the box casings 3 to the ship, a chain 26 is disposed in the box casings 3 at one side of the ship with one end thereof anchored as at 27 and when the chains are in use the free end thereof is removed from the inclosing box casing and passed beneath the hull of the ship as shown in Fig. 3 for attachment to the corresponding box casing at the opposite side of the ship.

Assuming that the bags are deflected as shown in Fig. 4, and contained within the box casings with the covers thereof closed as shown in Figs. 1 and 2, the switch device 40 25 is operated for causing a spark between the gap of the contact points 22 for igniting the wick 21. All of the wicks may be connected in a single circuit or individually operated and upon ignition of the wicks a 45 buoyant gas is produced in the receptacle 8 that escapes through the funnel portion 13 and through the neck 15 of the bag into the bag 14. When the bags are inflated, the same automatically open the cover walls 6 of the box casings and project upwardly of the box casings as shown in Fig. 3 and by dotted lines in Fig. 1, thus maintaining the boat floatative upon the surface of the water. The link connections 17 between the recep-

tacles 8 in the bags 14 combine with the strap connections 16 to maintain the bags 14 operatively connected to the receptacles while buoyant properties of the bags are sufficient to maintain the ship floating upon the surface of the water. Any type of wick 60 capable of producing a buoyant gas may be employed and it is not intended that the invention be limited to any particular form of gas producing agent.

While there is herein shown and described what is believed to be the preferred embodiment of the invention, it is nevertheless to be understood that minor changes may be made in the form, combination and arrangement of parts without departing from the 70 spirit and scope of the invention as herein-after claimed.

What is claimed as new is:

1. A ship raising device comprising in combination with a ship, a plurality of box casings secured to the deck of the ship, each casing including a hinged cover, a receptacle within the casing, a normally deflated bag in communication with said receptacle, a gas producing wick within the receptacle and 75 electrical means for igniting the wick.

2. A ship raising device comprising in combination with a ship, a plurality of box casings secured to the deck of the ship, each casing including a hinged cover, a receptacle within the casing, a normally deflated bag in communication with said receptacle, a gas producing wick within the receptacle, 80 electrical means for igniting the wick and connecting means extending between the gas 85 electrical means and the receptacle.

3. A ship raising device comprising in combination with a ship, a plurality of box casings secured to the deck of the ship, each casing including a hinged cover, a receptacle 95 within the casing, a normally deflated bag in communication with said receptacle, a tube extending into said receptacle, a wick within the receptacle having one end thereof secured in the inner end of the tube and an 100 electrical spark device within the tube adapted to be operated to ignite the wick.

In testimony whereof I affix my signature in presence of two witnesses.

JOSEPH VERCHAK.
